(57) **CLAIM**

The ornamental design for a loudspeaker, as shown and described.

DESCRIPTION

FIG. 1 is a top, right, front perspective view of a loudspeaker showing our new design;

FIG. 2 is a top, left, rear perspective view thereof;

FIG. 3 is front elevational view thereof;

FIG. 4 is a right side elevational view thereof;

FIG. 5 is a left side elevational view thereof;

FIG. 6 is a rear elevational view thereof;

FIG. 7 is a top plan view thereof;

FIG. 8 is a bottom plan view thereof;

FIG. 9 is a rear elevational view thereof, with active amplifier details;

FIG. 10 is a bottom, right, front perspective view of a second embodiment of a loudspeaker;

FIG. 11 is a top, left rear perspective view of FIG. 10;

FIG. 12 is a front elevational view of FIG. 10;

FIG. 13 is a right side elevational view of FIG. 10;

FIG. 14 is a left side elevational view of FIG. 10;

FIG. 15 is a rear elevational view of FIG. 10;

FIG. 16 is a bottom plan view of FIG. 10; and,

FIG. 17 is a rear elevational view thereof, with active amplifier details.

The broken lines environment is for illustrative purpose only and forms no part of the claimed design.
